**METHOD OF AND APPARATUS FOR CLEANING
INGOT PIECES**George Albert Lyon, 13881 W. Chicago Blvd.,
Detroit 28, Mich.Filed Nov. 23, 1955, Ser. No. 548,703
5 Claims. (Cl. 29—556)

The present invention relates to improvements in preparing ingot pieces for subsequent working thereon as for example by flattening the same and then drawing the same into shell form.

Steel ingots as they are produced by casting and soaking develop a scaly, pitted and otherwise imperfect "skin" or external surface. For some purposes, such as for drawing, it is highly desirable to have pure, clean metal free from surface impurities or imperfections which may otherwise be reflected in corresponding imperfections in the finished article such as a drawn shell.

For certain purposes, such as for drawing steel shells, metal pieces free from surface tensions is desirable. Material as derived directly from the ingot is highly advantageous for the purpose. However, the objectionable surface scale, imperfections, and the like must be eliminated before the ingot pieces can be successfully utilized for the purposes mentioned.

It is, accordingly, an important object of the present invention to provide an improved method of and apparatus for effectively treating and cleaning ingot pieces preparatory to further working of the pieces.

Another object of the invention is to provide an improved method of removing scale and other impurities and imperfections from the surface of ingot pieces.

A further object of the invention is to provide novel apparatus for not only applying internal scale removing pressure to ingot pieces but also superficial scale and impurity and imperfection removing scrubbing action.

Still another object of the invention is to provide an improved method of preparing and cleaning ingot pieces by combination of internal and external actions thereon.

Other objects, features and advantages of the present invention will be readily apparent from the following detailed description of a preferred embodiment taken in conjunction with the accompanying drawing, in which:

FIGURE 1 is a side elevational view of an ingot piece substantially as it appears after severance from the ingot;

FIGURE 2 is a vertical sectional elevational view showing more or less schematically apparatus for practicing the method of the present invention;

FIGURE 3 is a top plan view taken substantially along the line III—III of FIGURE 2; and

FIGURE 4 is an end elevational view of a flattened disk blank prepared from a treated and cleaned ingot piece.

An ingot piece 5 (FIG. 1) is derived by severing it from a cast ingot that may be of the usual elongated tapered form, several feet in length and a foot or more in diameter, and generally circular in its longitudinal periphery although it may be fluted. The length of the ingot piece 5 is predetermined in relation to diameter to afford the desired mass of material for the article ultimately to be made therefrom. An example of such an article is a drawn steel shell of substantial size. To this end, the ingot piece 5 is transformed into a flattened blank B (FIG. 4) of several times the original diameter of the ingot piece and only fractionally as thick. For large size shells such as bomb head shells for ordnance purposes or shells for industrial purposes such as tanks the blank B may have to be between one and two inches thick and from three to five feet in diameter.

For drawing purposes, the blank B must be as nearly

2

as practicable free from flaws and impurities not only internally but also on the surface. Accordingly, the ingot piece 5 is severed from a portion of the ingot that is free from piping or blow holes or end pits, with the opposite ends of the piece clean as a result of end cropping or cleaning off or severance of the ingot and then severance of the piece from the remainder of the ingot.

It is also highly important, of course, to have the longitudinal side or peripheral surfaces of the ingot free and cleaned of impurities such as scale, and imperfections such as pits or cracks. Moreover, it is desirable to eliminate the taper from the longitudinal wall surfaces of the ingot piece.

By the present invention, the ingot piece 5 is subjected to axial compression and a component of internal lateral expansion force or pressure for at least initiating dislodgment from the longitudinal periphery of the piece scale and impurities while also substantially equalizing the longitudinal periphery or diametrical shape of the piece. Furthermore, the longitudinal periphery of the piece is subjected to a scouring, scrubbing surface cleaning action such as may be accomplished by wire brushing.

Apparatus for carrying out the method is shown in FIGURES 2 and 3 and includes axial compression means comprising a lower supporting or anvil member 7 and an upper compression member 8. The lower anvil member 7 is supported for free rotation about a vertical axis by a base member 9 having means such as a journal bore 10 and thrust bearings 11 by which the member 7 is mounted to project upwardly above a table 12 also supported by the base 9.

For coaxial cooperation with the rotary supporting member 7, the compression member 8 is rotatably supported by a ram structure 13 capable of driving the member 8 toward the member 7 with sufficient compression thrust force to partially compress the ingot piece 5 to a shorter length and effect a lateral or radial bulging of the longitudinal peripheral wall surface of the ingot piece substantially as shown in FIG. 2, as visualized on comparison of the dash outline position of the ingot piece and the full line condition thereof, shown in FIG. 2.

In addition to axial compression of the ingot piece 5, the pressure member 8 also subjects the piece to a component of uniform radial pressure in the smaller diameter end portion thereof so as to substantially equalize the opposite end portions of the compressed ingot piece. This is accomplished by the provision on the thrust or pressure end of the member 8 of a shallow taper preferably substantially frusto-conical thrust tip 14 which on pressing into the opposing end of the ingot piece 5 displaces a limited amount of the material of the ingot piece radially outwardly coincident with the axial compression of the piece.

As a result of the axial compression to which the ingot piece 5 is subjected between the members 7 and 8, the longitudinal periphery of the piece is laterally or radially bulged and thereby expanded so that scale and impurities tend to crack off, and the flutes and cracks or pits are generally reduced to at least a substantially shallower depth if not eliminated.

It is desirable, however, to have the longitudinal periphery of the ingot piece 5 substantially clean and scoured or worked off or down to clean, substantially pure and flawless metal. To this end, means are provided in association with the supporting and compression members 7 and 8 for working off or dislodging or cleaning any remaining scale or impurities and removing enough of the cleaned periphery to eliminate objectionable imperfections. Herein such means comprise a pair of large wire brushes 15 suitably mounted on respective spindles 17 supported by journal members 18 carried by the

table 12. Each of the brushes 15 comprises a body 19 and a peripheral annular mass of wire bristles 20. The brushes 15 may be up to six feet in diameter and of a bristle thickness sufficient to make full substantially uniform contact over the entire length of the compressed, laterally bulged ingot piece 5.

By preference, the brushes 15 are mounted on vertical axes parallel to the axis of the supporting and compression members 7 and 8, and with the journal members 18 reciprocably guided for movement between clearance and working positions relative to the ingot or work piece.

5 To this end, the journal members 18 extend through respective elongated slots 21 in the table 12 radially disposed relative to the axis of the member 7, and with respective flange portions 22 of the journal members reciprocably guided parallel to the axes of the respective slots 21 by guide rails or gibs 23 on the table.

For reciprocating the brush journals 18 and thereby the brushes 15 relative to the work, means are provided such as respective fluid operators 24 which may be hydraulic or pneumatically actuated by manual or automatic control means. Piston rods 25 from the fluid operators are connected to the brush mechanism as for example to prime movers such as respective electric motors 27 for rotatably driving the brush spindles 17 and thereby the brushes 15. Thus, in operation, the brushes 15 may be rotated at suitable speed continuously by the respective motors 27 and the brush reciprocation actuators 24 will operate to move the brushes from the backed-off or clearance relation to the work into working relation thereto wherein the bulged periphery of the work piece is acted upon by the brush bristles 20 to abrade and scour the same clean and substantially flaw free. Preferably the arrangement is such that working pressure of the brushes is applied from diametrically opposite sides against the work piece and such pressure is controllable to be as great or as light or progressively increasing during the brushing operation, as is suitable for the work piece being cleaned, as controlled through the fluid operators 24.

For speed in operation and efficiency in the cleaning of the work piece periphery, the bulged ingot piece 5 is preferably rotated counter the rotation of the brushes. As shown by the arrows in FIGURE 3, for example, the brushes may be rotated clockwise and the work piece also rotated clockwise so that the peripheral direction of movement at contact of the brush bristles 20 with the work piece is in opposite directions.

For rotating the work piece 5, the compression member 8 is preferably rotated as by means of a prime mover such as an electric motor 28 mounted on the ram structure 13 and connected by a flexible driving means such as a belt or chain 29 with the member 8 as by means of a pulley or sprocket wheel 30 driven by the motor and a pulley or sprocket wheel 31 carried by the rotary member 8.

To assure positive turning of the ingot piece 5, interlock means are preferably provided between the compression member 8 and the work piece as for example by providing the compression thrust face 14 with keying lugs 32 which press corresponding keying slots 33 into the opposing surface of the ingot piece 5 as an incident to compression of the ingot piece. Thus, the ingot piece 5 is placed coaxially between the members 7 and 8 while the member 8 is backed away to a sufficient clearance distance and the brushes 15 are backed off to a clearance spacing, and then the ram 13 drives the compression member 8 against the ingot piece 5 to compress the same and effect an interlock therewith so that the ingot piece can be positively rotated relative to the brushes 15. Then when the brushes are brought into brushing engagement with the bulged periphery of the ingot piece 5, uniform, thorough cleaning of the bulged surface of the ingot piece is accomplished.

After the ingot piece 5 has been thoroughly cleaned, 75

it may be appropriately heated to a good plasticizing temperature such as from 2000° F. to 2200° F. in a manner to avoid oxidation or scaling, and then it is further compressed axially from the dash outline position of FIG. 4 into the flattened blank B which is then ready to be further processed as for example by dishing and cupping and then drawing the same into shell form.

It will be understood that modifications and variations may be effected without departing from the scope of the novel concepts of the present invention.

I claim as my invention:

1. In a method of descaling and/or removing surface impurities from an ingot piece having longitudinal side walls, compressing the piece axially between pressure members to shorten the piece and displace material thereof laterally for bulging the longitudinal side walls and thus cracking to initiate displacement of surface impurities therefrom, as an incident to the compression locking the piece to one of the members, while locked and held between the members rotating the piece by said one member, and while rotating the piece subjecting the longitudinal side walls thereof to progressively increasing abrading pressure of a rotating wire brush for cleaning the longitudinal side walls of any remaining impurities.

2. In a method of descaling and/or removing surface impurities from an ingot piece having longitudinal side walls, compressing the piece axially between pressure members to shorten the piece and displace material thereof laterally for bulging the longitudinal side walls and thus cracking to initiate displacement of surface impurities therefrom, as an incident to the compression locking the piece to one of the members, while locked and held between the members rotating the piece by said one member, and while rotating the piece subjecting the longitudinal side walls thereof to the action of rotating abrading means for substantially cleaning the longitudinal side walls of any remaining impurities.

3. In apparatus for treating ingot pieces, means for supporting an ingot piece axially, means for applying compression axially to the ingot piece toward said supporting means, one of said means having means for keying the same to the engaged face of the ingot piece incident to applying axial compression to the piece, means for rotating said one means to thereby rotate the ingot piece, and a pair of wire brushes disposed on axes parallel to the axis of the rotating piece and movable into abrading engagement with the longitudinal wall of the piece from diametrically opposite sides for cleaning the piece.

4. Apparatus for treating cast ingot pieces that have been cut from an ingot preparatory to flattening into disks to be drawn into shell form, supporting structure, thrust bearing means carried by said supporting structure, an anvil rotatably supported by said thrust bearing means and having an upwardly facing supporting surface, a ram structure movable vertically toward and away from said anvil and having a downwardly facing rotary compression member cooperatively opposing said anvil surface to apply axial compression to an ingot piece mounted on said anvil surface and engaged by the compression member during downward movement of the ram structure to squeeze the ingot piece axially and reduce its length and bulge out the longitudinal wall of the ingot piece for cracking off scale and impurities, means carried by the ram structure to rotate said compression member, keying means on the compression member and arranged to be pressed into the face of the ingot piece engaged by the compression member during compression of the ingot piece, and means carried by the supporting structure and movable from a backed off position into engagement with the bulged perimeter of the ingot piece after compression and while the ingot piece is rotated by rotation of the compression member by said means for rotating the same and by coincident rotation of the anvil through engagement thereof by the ingot piece for further cleaning of the bulged perimeter surface of the ingot piece.

5. Apparatus for treating cast ingot pieces that have been cut from a tapered ingot preparatory to flattening into disks to be drawn into shell form, and such pieces tapering from a smaller diameter end portion to a larger diameter end portion in each instance, supporting structure, thrust bearing means carried by said supporting structure, an anvil rotatably supported by said thrust bearing means and having an upwardly facing supporting surface, a ram structure movable vertically toward and away from said anvil and having a downwardly facing rotary compression member cooperatively opposing said anvil surface to apply axial compression to an ingot piece mounted with its larger diameter end portion at its lower end and disposed on said anvil surface and with its smaller diameter end portion extending upwardly and engaged by the compression member during downward movement of the ram structure to squeeze the ingot piece axially and reduce its length and bulge out the longitudinal wall of the ingot piece for cracking off scale and impurities, means carried by the ram structure to rotate said compression member, keying means on the compression member and arranged to be pressed into the face of the ingot piece engaged by the compression member during compression of the ingot piece, and means carried by the supporting structure and movable from a backed off 25 position into engagement with the bulged perimeter of

10

15

20

25

the ingot piece after compression and while the ingot piece is rotated by rotation of the compression member by said means for rotating the same and by coincident rotation of the anvil through engagement thereof by the ingot piece for further cleaning of the bulged perimeter surface of the ingot piece, said compression member having a substantially frusto-conical thrust tip which engages the opposing axial face of the ingot piece and displaces a limited amount of the material of the ingot piece radially outwardly coincident with axial compression of the piece in order to substantially equalize said smaller diameter upper end portion of the ingot piece with said larger diameter lower end portion of the piece.
